HEATER HOUSING FOR ELECTRIC HAIR CURLERS

Clifford E. Grube, Niles, Ill., assignor to
Associated Mills, Incorporated

Filed Dec. 28, 1970, Ser. No. 26,667

Term of patent 14 years

Int. Cl. D28—03

U.S. Cl. D86—10 E

Fig. 1

Fig. 2

Fig. 3

Fig. 4

FIG. 1 is a front perspective view of a heater housing for electric hair curlers showing my new design;

FIG. 2 is a side elevational view thereof;

FIG. 3 is a front elevational view thereof; and

FIG. 4 is a top plan view thereof.

The bottom and rear of the heater housing for electric hair curlers is substantially plain and unornamented.

I claim:

The ornamental design for a heater housing for electric hair curlers, as shown and described.
